UNITED STATES PATENT OFFICE.

HARRY C. FOSTER, OF CONNERSVILLE, INDIANA, ASSIGNOR, BY DIRECT AND MESNE ASSIGNMENTS, OF ONE-HALF TO INDIANA LAMP CORPORATION, OF CONNERSVILLE, INDIANA, A CORPORATION OF DELAWARE, AND ONE-HALF TO GENERAL MOTORS CORPORATION, OF DETROIT, MICHIGAN, A CORPORATION OF DELAWARE.

LAMP FOCUSING.

Application filed January 29, 1925. Serial No. 5,529.

This invention relates to lamp focusing and is herein illustrated as embodied in focusing devices for the lamps of automobile headlight reflectors.

5 In automobile headlights, in use at the present day, one of the main sources of glare is due to the fact that the lamps are out of focus.

One of the objects of this invention, therefore, is to provide an easily accessible focusing device capable of accurately adjusting a filament into focus and maintaining it in adjustment. Another object is to provide an improved focusing device for adjusting 10 a lamp longitudinally of the reflector axis or transversely thereof in any desired direction and to a fine degree. Another object is to provide a reliable focusing device of very simple, compact, and inexpensive construction.

20 To these ends and also to improve generally upon devices of the character indicated my invention consists in the various matters hereinafter described and claimed.

25 In the drawings, Figure 1 is a central vertical section.

Figure 2 is a front elevation with the reflector partly broken away.

Figure 3 is a rear elevation with the reflector partly broken away.

Figures 4, 5, 6 and 7 are vertical sections of other forms of the invention.

Figure 8 is a transverse section on the line 8—8 of Figure 7.

35 Figures 9 and 10 are central vertical sections of other forms of the invention and

Figure 11 is a transverse section on the line 11—11 of Figure 10.

The numeral 10 designates a parabolic reflector which, in each instance, has a central opening through which a lamp socket or sleeve 11 is longitudinally movable. This reflector is mounted in the usual casing, a portion of which is indicated at 8. Held

40 in the socket, is the usual lamp bulb 12 having a centrally arranged filament 13. The bulb 12 is removably secured in the socket by the usual pin 14 and bayonet slot 15. In Figure 1, a perforated plate 16, having a 45 peripheral flange 17, closely surrounds the socket 11. The inner edge of the plate is curled about the rim of the opening in the reflector to form a support on which the

socket 11 can slide and tilt. The flange 17 bears against a packing ring 18 to cushion 55 its engagement with the reflector. A second flanged and perforated plate 19, which may be stamped out by the same die as the plate 16, is fixed in any suitable way to the socket 11.

50 Passing loosely through aligned openings in the two plates 16 and 19 are a series of bolts 20, herein shown as three, which have their heads 22 accessible through openings 24 in the reflector at the sides of the lamp.

The heads of the bolts are maintained in contact with the inner face of the plate 16 by coil springs 21 interposed between the plates. Each bolt hole in the disc 19 is larger than its bolt and a nut 23 is threaded on each bolt 70 and held against turning by the outer flange of the plate 19. By turning all the bolts to the same degree, the socket 11 will be longitudinally shifted through the opening in the reflector. By turning the bolts in varying 75 degrees, the plate 19 can be tilted and, by reason of its rigid connection with the socket 11, the latter will be likewise tilted about the rim of the opening in the reflector which acts as a fulcrum.

This action naturally 80 forces the plate 19 to one side or another of its axis, this movement being permitted by the openings in the plate. Hence, the lamp filament has universal adjustment laterally or transversely to place it exactly in 85 the axis of the reflector and it also has longitudinal adjustment to place it at the focus.

Lighting current is supplied through the usual flexible conductor 32 extending from the rear of the socket 11.

90 In Figure 4, the reflector 10 has outwardly pressed portions 116 to form seats for the bolt heads 22 and the rim of the central opening is curled to form a fulcrum on which the socket 11 can tilt.

95 In Figure 5, the lamp is adjustable from the rear of the lamp casing 33, through holes 34, rather than from the front of the reflector, although, if desired, both ends of the bolts may be slotted and aligned openings 100 formed in the reflector will enable adjustment to be made from either end. In this figure, a flanged plate 216 holds the nuts 23 from turning and the plate has a sleeve portion 30 with its edge bent around the edge 105 of the reflector. A felt sleeve 29 makes the

opening dust proof and will yield when the socket tilts. To prevent access of dust from the rear of the casing, the openings 34 may be closed by a turnable disc 35 having openings 36 which can be made to register with the openings 34.

In Figure 6, the bolts 20 are not connected with the reflector, except through the lamp casing, but are passed loosely through the lamp casing 33 and have their heads 22 outside. In this case a plate 119 with flanges extending forwardly holds the nuts from turning and the springs 21 are inserted between the plate and the casing 33.

15 In Figure 7, the reflector 10 has a bead 37 at the rim of its central opening but this opening is larger than the socket 11 to allow clearance. A washer or sleeve-like piece of flexible material 38 may be attached to the 20 bead to close the space. The socket 11, in this form, is extended through the back of the casing 33 to receive the usual plug from which current is supplied to the lamp. The opening in the casing is also larger than the 25 socket and a flanged washer 39 closely fitting the socket 11 closes the opening. A coil spring 221, interposed between the washer 39 and a flanged plate 119 fixed to the socket, holds the washer against the inner 30 face of the casing and holds the bolt heads 22 against the outer face of the casing. The tilting of the socket in this form will take place about an axis near the plane of the plate 119 and the ends of the socket move 35 in opposite directions.

In Figure 9, there is a clearance between the socket 11 and the reflector and between the socket and the lamp casing 33 and a felt pad 138 closes the opening in the reflector. 40 The casing 33 has a pressed out central portion with a rolled flange 40 for holding the larger end of a volute spring 321, the smaller end of the spring abutting the rear face of the flanged plate 119.

45 Figure 10 is similar to Figure 6 but the space between the reflector 10 and the casing 33 is so great that a second socket 41 is placed in line with the socket 11 to receive the usual plug. The socket 41 is carried by 50 a flanged plate 42 held in an opening in the

casing 33' by bolts 20. A slack flexible conductor 43 allows the socket 11 to tilt without impairing the electrical connection. The plate 219 has its inner and outer flanges extending in opposite directions from the body 55 of the plate and this plate and the plate 42 may be stamped up by the same die.

In each form of the invention, the reflector and the casing provide a compartment for the focusing device which is accessible for 60 operation from the outside.

Although the invention has been illustrated by reference to certain illustrated forms, it should be understood that, in its broader aspects, the invention is not necessarily limited to the specific construction 65 selected for illustrative purposes.

I claim:

1. In a device of the character described, a reflector having a central opening, a lamp socket slidable longitudinally through the opening and adapted to tilt on the rim of the opening, a lamp in the socket, and a plurality of independently operable bolts connected to the socket and to the reflector for sliding 70 or tilting the socket.

2. In a device of the character described, a reflector having a central opening, a lamp socket slidable longitudinally through the opening and adapted to tilt on the rim of the 80 opening, a lamp in the socket, a plate fixed to and surrounding the socket, a plurality of independently operable bolts connecting the plate and the reflector, and springs surrounding the bolts and interposed 85 between the plate and the reflector.

3. In a device of the character described, a reflector having a central opening, a lamp socket slidable longitudinally through the opening and adapted to tilt on the rim of the 90 opening, a lamp in the socket, a flanged plate fixed to and surrounding the socket, a plurality of independently operable bolts connecting the plate and the reflector, springs 95 interposed between the plate and the reflector, and nuts held from turning by the flanged plate and threaded on said bolts.

In testimony whereof I affix my signature.

HARRY C. FOSTER.
